UNITED STATES PATENT OFFICE.

EUGENE R. CARICHOFF, OF SCHENECTADY, NEW YORK, ASSIGNOR TO GENERAL ELECTRIC COMPANY, A CORPORATION OF NEW YORK.

CIRCUIT-INTERRUPTING DEVICE.

1,164,257.

Specification of Letters Patent. Patented Dec. 14, 1915.

Application filed December 26, 1912. Serial No. 738,527.

To all whom it may concern:

Be it known that I, EUGENE R. CARICHOFF, a citizen of the United States, residing at Schenectady, county of Schenectady, State 5 of New York, have invented certain new and useful Improvements in Circuit-Interrupting Devices, of which the following is a specification.

My invention relates to interrupting 10 means for electric circuits and has for its object the provision of a device of this character which will effectively interrupt an electric circuit and extinguish the arc which is formed in a safe and efficient manner.

15 My invention relates more specifically to arc extinguishing devices of the character in which a magnetic circuit is caused to act upon the arc to disrupt it, such devices being commonly known as "magnetic blowing

20 outs." It is well known that when an arc is formed along a line parallel to a conductor in which current is flowing, the direction of current flow in the arc and in the conductor being the same the arc will be attracted to-

25 toward the conductor. This is so by reason of the attractive force existing between the lines of force in the space between the conductor and the arc since in this space the lines of force in two magnetic fields will be

30 parallel and in opposite directions. This effect is augmented by the repulsion effect existing between the lines of force beyond the arc in a direction away from the conductor. Likewise if the current in the con-

35 ductor is in the opposite direction from that in the arc the latter will be repelled.

In utilizing the magnetic field for blowing out an arc it is common to cover the pole pieces between which the arc is formed with 40 insulating material so as to prevent the arc from coming in contact with the pole-pieces. Frequently no attempt is made to keep the arc out of contact with the insulation and in some cases the arc is intentionally blown

45 against the insulating covering of the pole-pieces. Even if the arc is not intentionally blown against the pole-pieces the magnetic attraction between the iron pole-pieces and the arc will cause the arc to impinge against

50 the covering of the pole-pieces. It has also been proposed to have the arc blown against the magnetizing coil so that the arc will be

55 broken by encircling the coil. I have found that the most efficient and lasting arrangement is to have the arc blown away from the

coil in such a manner that it will be kept out of contact with the pole-pieces or the sides of the arc chute. In carrying out my invention I so arrange the parts that the magnetic flux in the pole-pieces repels the 60 arc and causes it to maintain a position intermediate the pole-pieces while it is being blown out. The arrangement is also such that the arc is blown in a direction away from the magnetizing coil. 65

In the accompanying drawing illustrating one embodiment of my invention, Figure 1 is a diagrammatic view illustrating the ordinary form of magnetic blow-out of the prior art; Fig. 2 is a diagrammatic view of a magnetic blow out construction in accordance with my invention, and Figs. 3 and 4 show an electromagnetic switch provided with my improved magnetic blowout. 70

Referring first to Fig. 1, 10 represents the 75 magnetizing coil of a blow-out of ordinary form having a core 11 and pole-pieces 12 and 13 extending laterally from the core 11. For purposes of illustration these pole pieces 12 and 13 are shown as being parallel with 80 each other and at right angles to the core 11. The circuit breaking contacts are located between the pole-pieces 12 and 13 and the arc formed between these contacts is represented by the conductor 14. Assuming that current is passing through the coil 10 from the terminal 15, the direction of flux through the core and pole-pieces will be as shown by the arrows extending along the pole-pieces. Assuming that the current through the contacts and hence through the arc 14 is in a 85 direction at right angles to the plane of the paper and flowing from the back to the front of the paper, the direction of the lines of force surrounding the arc will be as shown by the arrows. It will be seen that the lines of force in the pole-piece 12 are 90 parallel with and in the opposite direction from the lines of force surrounding the arc and between the arc and the pole-piece so 95 that the arc will be attracted toward the pole-piece 12. It is also seen that the lines of force in the pole-piece 13 are parallel with and in the opposite direction from the lines of force surrounding the arc 14 and 100 between the arc and the pole-piece. The arc will therefore be attracted toward the pole-piece 13. In other words, the arc is drawn toward both pole-pieces. Looking now at the lines of force in the space between the 105

110

two pole-pieces it will be noted that the direction is from the pole-piece 12 to the pole-piece 13. The lines of force, therefore, surrounding the arc and between the arc and the coil 10 will be in the same direction and will therefore cause the arc to be repelled from the coil. This repulsion is augmented by the attraction between the lines of force surrounding the arc and the lines of force 5 in the space between the pole-pieces but on the side of the arc away from the coil. With this arrangement, therefore, the arc, while it would be repelled from the coil, would be blown toward the pole-pieces. It will be ob- 10 served that if the current through the contacts and the arc 14 should be reversed from the direction shown in the drawing the arc will be repelled away from the pole-piece but will be attracted toward the coil. 15 In Fig. 2 which illustrates my present invention the arc will be repelled from the pole-pieces and also repelled from the magnetizing coil. This I have accomplished by causing the lines of force in the portion of 20 the pole-pieces adjacent the arc to be re- 25 versed with reference to the direction of the lines of force in the main body of the pole- pieces. By looking at this figure it will be seen that the directions of the flux in the 30 pole-pieces 17 and 16 are the same as in the pole-pieces 12 and 13 respectively of Fig. 1 and the direction of the flux, therefore, be- 35 tween the pole-pieces is the same as before. The direction of the current through the arc 40 is also the same as in Fig. 1. As shown in the drawings, the flux in the bent ends 18 and 19 of the pole-pieces is in the reverse direction from that in the main body of the pole-pieces. The direction of the flux, how- 45 ever, between the pole pieces is not changed. Following now the direction of the lines of force as indicated by the arrows it will be found that the flux in the end portions 18 and 19 of the pole-pieces is parallel with and 50 in the same direction as the flux in the field surrounding the arc and the arc will there- 55 fore be repelled from both poles and thus be forced to assume a position intermediate the poles. It will be noticed, however, that 60 the direction of the flux in the field between the pole-pieces is the same as the direction of the flux surrounding the arc and between the arc and the winding so that the arc will be repelled from the winding. This effect 65 will be augmented by the attraction between the lines of force in the two fields on the side of the arc away from the winding. The re- 70 sult of this arrangement is that the arc is not only repelled from the pole-pieces but 75 is also blown away from the winding. It 80 will be understood, of course, that I have 85 illustrated in this figure one method of carrying out my invention and that it is not intended that my invention should be limited 90 to the particular arrangement shown.

In Figs. 3 and 4 I have shown my invention applied to an electro-magnetic switch of standard design. Referring to these figures it will be seen that the actuating winding 20 operates the core 21 to lift the 70 pivoted switch arm 22 provided with the contact 23 into engagement with the stationary contact 24. These contacts 23 and 24 are located in an arc chute composed of plates 25 of insulating material extending 75 downwardly from the magnetizing winding 26 over the contacts. Secured to the ends of the core 27 of the magnetizing winding are the pole-pieces 28 and 29 which project downwardly along the outside of the in- 80 sulating plates 25 of the arc chute. These pole-pieces extend laterally from the core 27 and then fold inward. The inner folds of the pole-pieces are in contact with the plates of the arc chute and at the lower ex- 85 tremity are held in position by the bolts 30. It will be noted that the pole-pieces are pro- 90 vided with slots 31 which tend to prevent the lines of force from going across the pole- pieces diagonally but this is not an essen- 95 tial feature of my invention which is in no sense limited to the particular arrangement of the pole-piece or other parts shown. The arc which is formed between the contacts 23 and 24 will be intermediate the polepieces 100 28 and 29; that is, it will occur in a position substantially midway between the backward folds of these two polepieces. Whether or not the arc occurs at an exactly central position between the polepieces will make no 105 difference so far as the operation of the de- 110 vice is concerned, nor will it make any difference if the arc is formed somewhat in- 115 ward toward the coil from the ends of the folded back portions as shown in Fig. 3, 110 since the tendency of the flux will always be to force the arc toward the central position between the polepieces and outward away from the coil. The general shape of the pole-pieces is the same as that shown in 115 Fig. 2, and accomplishes the same result, namely, the forcing of the arc which forms between the contacts 23 and 24 away from the coil 26 and at the same time preventing it from impinging upon the sides of the arc 115 chute.

It should be understood that I do not limit my invention to the particular arrangement shown since various modifications of my invention will suggest themselves to those 120 skilled in the art without departing from the spirit of my invention, the scope of which is set forth in the annexed claims.

What I claim as new and desire to secure by Letters Patent of the United States, is:— 125

1. The combination with arc forming contacts, of a blow-out device therefor comprising a magnetizing winding in series with the contacts having pole-pieces between which the arc is formed and means whereby the 130

- magnetic flux generated by a current in said winding in the portion of the pole-pieces adjacent the arc repels the arc away from the pole-pieces.
5. 2. The combination with arc forming contacts, of a blow-out device therefor comprising a magnetizing winding in series with the contacts having pole-pieces between which the arc is formed and means whereby the magnetic flux generated by a current in said winding repels the arc away from the winding along a path intermediate of the pole-pieces.
- 10 3. The combination with arc forming contacts, of a blowout device therefor comprising a magnetizing winding in series with the contacts having pole-pieces between which the arc is formed and means whereby the magnetic flux in said pole-pieces generated by a current in said winding repels the arc away from the pole-pieces and the flux across the space in which the arc is formed causes the arc to move away from the winding.
- 15 20 25 4. The combination with arc forming contacts, of a blow-out device therefor comprising a magnetizing winding in series with
- the contacts having pole-pieces between which the arc is formed extending laterally from the axis of said winding and means whereby the magnetic flux in the portion of said pole-pieces adjacent the arc generated by a current in said winding repels the arc away from the pole-pieces and the flux across the space in which the arc is formed causes the arc to move away from the winding.
- 30 35 40 45 50 5. The combination with arc forming contacts, of a blow-out device therefor comprising a magnetizing winding in series with the contacts having pole-pieces between which the arc is formed extending laterally from the axis of said winding said pole-pieces being turned inward adjacent the contact to change the direction of the flux in the turned portion with reference to the direction of the flux in the unturned portion of the pole-pieces.

In witness whereof, I have hereunto set my hand this 24th day of December, 1912.

EUGENE R. CARICHOFF.
